UNITED STATES PATENT OFFICE.

HOPKIN THOMAS, OF CATASAUQUA, PENNSYLVANIA, ASSIGNOR OF ONE-HALF TO
WILLIAM R. THOMAS, SR., OF CATASAUQUA, PENNSYLVANIA.

FRICITION-CLUTCH.

1,110,972.

Specification of Letters Patent. Patented Sept. 15, 1914.

Application filed December 9, 1912. Serial No. 735,869.

To all whom it may concern:

Be it known that I, HOPKIN THOMAS, a citizen of the United States, residing at Catasauqua, in the county of Lehigh and State of Pennsylvania, have invented certain new and useful Improvements in Friction-Clutches, and I do hereby declare the following to be a full, clear, and exact description of the invention, such as will enable others skilled in the art to which it appertains to make and use the same.

This invention relates to friction clutches and the object of the invention is to provide improved means for throwing the driven mechanism into engagement with the driving mechanism.

A further object of the invention is to provide mechanism for converting horizontal motion along the shaft into rotary motion, which rotary motion is converted into radial motion by other mechanism for setting the driven mechanism against the driving mechanism.

With these and other objects in view the invention comprises certain novel constructions, combinations, and arrangements of parts as will be hereinafter more fully described and claimed.

In the drawings:—Figure 1 is an end elevation of my invention looking at the driven member. Fig. 2 is a section taken on line 2—2 of Fig. 1. Fig. 3 is a section on line 3—3 of Fig. 1. Fig. 4 is an end elevation of a modified form. Fig. 5 is a section taken on line 5—5 of Fig. 4. Fig. 6 is the detail of the toggle used in the modified form shown in Figs. 4 and 5.

Like reference characters designate corresponding parts throughout the several views.

Generally this invention aims to provide a driving member having concentric flanges, a disk comprising a driven member, a ring associated with the disk, and lever and toggle mechanism associated with the ring for forcing the oppositely moving shoes of the driven member against the flanges of the driving member, as the ring moves relative to the disk.

In the drawings, referring particularly to Figs. 1, 2 and 3 there is shown as keyed to a shaft 1, a driving member 2 having projecting flanges 3 and 4, which flanges are concentric with shaft 1. Keyed to a shaft 1'

is a disk 5 having hubs 6 extending on either side thereof, the hubs presenting a comparatively large area for the support of the comparatively narrow disk 5. Extending from disk 5 is a plurality of lugs 7, six in number, as shown in Fig. 1, though any suitable number may be used. The sides of these walls extend preferably perpendicular to the plane of the disk 5 and adjacent walls of adjacent lugs are made parallel so that there is defined between adjacent lugs openings 65 having parallel sides. The faces of the lugs 7 are provided with arcuate slots 8 which are adapted to receive a ring 9, which ring is concentric with shaft 1'. Pivoted as at 10 to the ring 9 is a plurality of pairs of toggle links, the outwardly extending member 11 of each pair of toggle links being pivoted to a shoe 12, the outer surface of which is curved to conform to the outline of flange 3. A reduced portion extending from the shoe 75 12 forms a tongue 13, the sides of which are engaged by the lugs 7, the object of the lugs 13 being to guide the shoe 12 between the lugs 7 so that said shoes may move only in a radial direction. The other toggle link 14 of each pair also pivoted at 10 is pivoted to a shoe 15, which shoes have outwardly extending lips 16, which lips are adapted to loosely engage the tongues 13, it being understood that the sides of the lips 16 engage 85 the walls of adjacent lugs so that the shoes 15 may move only in a radial direction. By referring to Fig. 3 it will be seen that the ring 9 is mounted between the tongue 13 and the toggles 11 and 14. While this particular construction of the lip 16 and tongue 90 13 has been described, it is to be understood, of course, that their positions could be interchanged so that the outwardly extending lip 16 of the shoe 15 would engage the ring 95 9. Passing through the ring 9 is a suitable bolt 17, the upper end of which is cylindrical and adapted to move in a slot 18 of an arm 19, which arm is provided with a trunnion 20. Keyed to the trunnion 20 is an arm 21, curved as shown in Fig. 1, and having swivelly connected to the outer end 22 thereof link 23, which link 23 may be hinged to parallel ears extending from collar 24, or may be swivelly connected to the collar 24. In 105 understanding the operation of setting the shoes against the flanges, it may be convenient to consider the arms 19 and 21 as

constituting a lever, insomuch as the said arms are rigidly connected together. The line passing through the center of trunnion 20 and outer end 22 of the arm 21 is designed to pass considerably to one side of the center of the shaft 1', so that as the end 22 descends the arm 21 may be rotated about trunnion 20. Also, the line passing through the center of the trunnion 20 and the bolt 17 is designed to extend considerably to one side of the center of the shaft 1'. Likewise, a line passing through the center of the shaft 1', the point where toggle link 14 is pivoted to shoe 15, and the point where the toggle link 11 is pivoted to shoe 12 is to one side of the pivoted point 10, so that as the pivoted point 10 is drawn nearer this line the shoes will be separated.

In the operation of this device, when it is desired to throw the driven member into engagement with the driving member the collar 24 is moved longitudinally of the shaft away from the driven member, at which time the link 23 will draw end 22 of the arm 21 toward the shaft, which will result, as above described, in the turning of arm 21 about the trunnion 20. As the arm 21 turns and carries the slotted arm 19 which is keyed to it, the bolt 17 is engaged by the slot 18 and moved in the same angular direction as arm 21. Inasmuch as bolt 17 is secured to ring 9 all of the pivoted points 10 will be moved toward the line joining the points where the toggle links engage their respective shoes, which will result in the separating of the shoes on a radial line, such separation being guided by the tongues 13, and lips 16 move between the parallel sides of extending lugs 7.

In the modified form shown in Figs. 4, 5, and 6, a plurality of levers 25 are shown as provided with slots 26 which engage bolts 27 carried by a ring 28', which ring 28' corresponds to the ring 9 in the form shown in Figs. 1 and 2. In this form the toggle joints 28 shown more particularly in Fig. 6 are provided with a central opening through which passes a bolt 29 the outer end of which is reduced and threaded to receive nuts for suitably securing same to the disk 5, this bolt being keyed to the toggle joints 28. One end of each of the toggle joints 28 is provided with a trunnion 30 adapted to move in a semi-cylindrical slot formed in shoe 31, while the other end of the toggle joint is provided with trunnions 32 adapted to be received by corresponding semi-cylindrical slots in the shoes 33. As in the preferred form the line joining the centers of these trunnions passes to one side of the center of the shaft 1'. One of the bolts 29 is extended as shown at 34, and has keyed thereto an arm 35 to the outer end 36 of which is swivelly connected a link 37. This link 37 may be connected to the collar 24 in

a manner similar to that shown in the preferred form, and the line joining the center of the extension 34 with outer end 36 passes considerably to one side of the center of the shaft 1'. In the operation of this modified form when it is desired to throw the driven member into engagement with driving member, the collar 24 is moved longitudinally of the shaft away from the driven member as in the preferred form, at which time the end 36 of the arm 35 will be drawn outwardly, which will result in the turning of the extending end 34. By means of the adjacent lever 25 this turning movement of the extending end 34 is conveyed to the ring 28', and from ring 28' rotary motion is conveyed to the remaining toggle joints 28 by means of their respective levers 25. Inasmuch as the line passing through trunnions 30 and 32 pass to one side of the center of the shaft, as the toggles turn shoe 31 will be drawn outwardly against flange and shoe 33 will be thrown inwardly against flange 4, at which time the driven member will be made to revolve with shaft 1'. 70 75 80 85 90 95 100

What I claim is:—

1. In a friction clutch, a driving member having concentric flanges, a driven member comprising a set of shoes adjacent each flange, toggle joints interposed between the opposite shoes of the sets of shoes, the axes of the toggle links forming the toggle joints passing to one side of the center of the flanges, a ring connected to the toggle joints and means for actuating the ring. 105

2. In a friction clutch, a driving member, a disk forming a driven member, a ring carried by the disk, toggle joints actuated by the ring, shoes adapted to grip the driving member and engaging the toggle joints, said shoes held against lateral movement with respect to the driven member, the axes of the toggle links forming the toggle joints passing to one side of the center of the ring, and means for rotating the ring. 110

3. In a friction clutch, a driving member, a driven member, a ring carried by the driven member, expandable means connected to the ring adapted to expand and engage the driving member as the ring rotates, a pin carried by the ring, a lever pivoted to the driven member, one arm of which engages the pin, and means for moving the other end of the lever to rotate the ring. 115

4. In a friction clutch, a driving member having flanges integral therewith, a disk, lugs formed integral therewith, adjacent sides of adjacent lugs being parallel, shoes provided with means for guiding the same between the lugs, said shoes being adapted to engage the flanges, and means carried by the disk adapted to move the shoes relative to each other. 120 125

5. In a friction clutch, a driving member having concentric flanges integral therewith, 130

- a rotatable disk, a ring carried by the disk, shoes engaging the flanges, lugs carried by the disk and located between the shoes to guide the same, pairs of toggle links pivoted 5 to the ring, one toggle link of each pair being pivoted to a shoe engaging the outer flange, the other toggle of each pair being pivoted to a shoe engaging the inner flange, and means for rotating the ring.
- 10 6. In a friction clutch, a driving member having concentric flanges integral therewith, a disk, lugs formed integral with the disk, the adjacent sides of adjacent lugs being parallel, shoes engaging the flanges, projections extending from the shoes, said projections engaging the parallel sides of adjacent lugs, and means mounted on the disk 15 and engaging the shoes for moving the said shoes apart.
- 20 7. In a friction clutch, a driving member having concentric flanges integral therewith, a disk, lugs integral with the disk, the adjacent sides of adjacent lugs forming an opening having parallel sides, shoes engaging each flange, each shoe having a reduced portion extending therefrom and engaging the parallel sides of the opening, the reduced portions of the shoes engaging the sides of the openings, and engaging each 25 other, a ring carried by the disk, means pivoted to the shoes and ring for moving the shoes to and from the flanges as the ring moves, and means for actuating the ring.
8. In a friction clutch, a driving member 30 having concentric flanges integral therewith, a disk, lugs formed integral with the disk, the adjacent sides of adjacent lugs being parallel, shoes engaging the flanges, projections integral with the shoes and engaging the parallel sides of the lugs, a ring, 35 toggle joints connected to the ring, some of the toggle links forming the toggle joints being pivoted to the shoes engaging the outer flange, others of the toggle links being pivoted to the shoes engaging the inner 40 flange.
9. In a friction clutch, a shaft having a driving member mounted thereon, a collar longitudinally movable on the shaft, a disk 45 mounted on the shaft, a lever pivoted in the disk, a link connecting the collar and one end of the lever, a ring engaged by the other end of the lever, toggle links carried by the ring, and shoes pivoted to the toggle links and adapted to engage the driving member 55 as the lever moves the ring.
10. In a friction clutch, a shaft having a driven member mounted thereon, a collar 60 slidable on the shaft, a link pivoted to the collar, an arm swiveled to the link, a ring, means associated with the ring and arm for rotating the ring as the arm rotates, and shoes adapted to engage the driving member, and means engaging the shoes and ring for moving the shoes in engagement with the 65 driving member as the ring rotates.
11. In a friction clutch, a shaft having a driving member secured thereon, a collar 70 loosely mounted on the shaft, a link pivoted to the collar, a disk mounted on the shaft, an arm pivoted in the disk, one end of the arm being swivelly connected to the link, a ring, means for connecting the ring and the arm, and shoes associated with the ring and adapted to engage the driving member as 75 the ring rotates.
12. In a friction clutch, a shaft having a driving member secured thereon, a collar 80 slidable upon the shaft, a link pivoted to the collar, a disk mounted on the shaft, a lever 85 pivoted in the disk, one arm of the lever being connected to the link, the other arm being slotted, a ring, a pin carried by the ring, and engaged by the slotted arm, shoes adapted to engage the driving member, and 90 mechanism associated with the ring and shoes for setting the shoes as the ring rotates.
13. In a friction clutch, a shaft having a driving member mounted thereon, a collar 90 longitudinally movable on the shaft, a disk mounted on the shaft, a lever pivoted to the disk, means associated with the collar and one arm of the lever for rotating the lever as the collar slides on the shaft, a ring, the 95 other end of the lever engaging the ring and adapted to rotate the same as the lever rotates, shoes adapted to engage the driving member, and means interposed between the shoes and ring for moving the shoes as the 100 ring rotates.

In testimony whereof I affix my signature in presence of two witnesses.

HOPKIN THOMAS.
